PRINTING DEVICE FOR STATISTICAL, CALCULATING, AND TABULATING MACHINES UTILIZING PERFORATED CARDS

Knut Andreas Knutsen, Paris, France

Application March 30, 1933, Serial No. 663,628
In France April 9, 1932

16 Claims. (Cl. 101—91)

The present invention has for its object a printing device particularly adapted to be used in combination with statistical, calculating and tabulating machines utilizing perforated cards.

5 The printing device according to my invention is such that a wheel carrying the types is given, at the time of the printing, a rolling movement with respect to the surface of the paper, so that the instantaneous absolute velocity of the point 10 of contact with the paper may be zero. To this effect, the printing device can be made as described in my U. S. Patent application Ser. No. 540,166, filed May 26, 1931, and especially as disclosed in my U. S. patent application Ser. No. 15 545,121, filed June 17, 1931, and comprises a movable carriage or support on which is mounted the type carrying wheel, and also transmission means for operatively connecting the spindle of said wheel to a toothed wheel rotating synchronously with the main shaft of the machine. When 20 a type of the type carrying wheel is to be printed, a toothed organ carried by an oscillating lever comes into mesh with one of the toothed wheels of the carriage or support and then acts as a 25 stationary rack for said wheel so that the carriage or support is given a translatory movement in the course of which the type carrying wheel comes into contact with the paper as if it rolled thereon.

30 The object of my invention is to provide a device of that character in which the type to be printed, the velocity of which in a direction parallel to the paper is zero, is given, at the very time of the printing, a sudden movement toward the 35 surface of the paper, which produces the striking of said type against the paper.

In an embodiment of my invention, this result is obtained by means of a guiding surface of suitable outline that acts on the carriage so 40 that the type carrying wheel may be given, besides its rolling movement on the paper, a sudden movement toward the surface of the paper which produces the striking of the type to be printed against said paper.

45 Another object of my invention is to provide a printing device of that kind such that each of the type carrying wheels comprises a great number of signs, thirty or more for instance, which can be printed selectively according to the location of the perforations that are provided in the 50 columns of the cards that pass through the tabulating machine.

In order to obtain this result, while keeping the usual size for the cards, which comprise, for 55 instance, in each column, twelve lines capable of

receiving perforations, the individual, or single, perforations which correspond to certain signs according to the rank that they occupy in the columns of the cards are completed by other perforations, forming groups in said columns, 5 which correspond to other signs. For instance the first lines of the card, that is those with which the contact device first comes into register, are reserved, so that a perforation made in one of said lines corresponds in itself to no sign, while 10 in the following lines, each perforation corresponds individually to a letter or a sign. Under these conditions, a certain number of signs can be represented by a perforation made in one of the reserved lines combined with a second perforation made in one of the following lines. By 15 way of example, if it be supposed that each column of the card comprises twelve lines, the two first lines will correspond to no letter and the alphabet will begin at the third line. A perforation in this third line represents letter A, a 20 perforation in the fourth line letter B, and so on as far as letter J, which will be represented by a perforation in the twelfth line. The letters following letter J will be represented by the combination, 25 in the same column, of a perforation in the two reserved lines with a perforation in one of the other lines. Thus K will be represented by a perforation in the first line and a perforation in the third line, L by a perforation in the first 30 line and one in the fourth line, and so on.

Each printing device comprises, in combination with the type carrying wheel, a selecting device actuated by the contact device or card examining device either electrically or mechanically and 35 which determines the printing of the character or sign of the type carrying wheel that corresponds to the rank, or ranks, of the perforation, or perforations, met by the contact device in a given column.

40 In an embodiment of my invention, this selecting operation is performed as follows: The type corresponding to a character is located on the type carrying wheel a given number of positions away from the character that precedes it in a 45 standard list of said characters. In other words, each letter is located a given number of positions away from the preceding letter of the alphabet. This given number of positions is advantageously equal to three. Thus A being the first letter on 50 the wheel, B is the fourth letter, C is the seventh, . . . J is the twenty eighth. To each of these characters there corresponds a perforation in one of the lines following the two first ones, which are reserved. K is the third character, L 55

- is the sixth one, M is the ninth one, N is the twelfth one, and so on. To each of the last mentioned letters there corresponds two perforations, one in the first line of the card and the other one in one of the other lines starting from the third. U is the second character on the wheel, V is the fifth, W is the eighth, and so on. To each of the last mentioned letters there corresponds a group of two letters, one in the second reserved line and another one in one of the other lines starting from the third, and so on.
- The selecting mechanism operated either electrically or mechanically from the contact device, that is to say the mechanism that applies, at the proper time, a toothed sector acting as a rack against one of the toothed wheels of the set of wheels of the carriage and which therefore gives the carriage and the type carrying wheel their printing displacement, comprises a cam driven synchronously with the main shaft of the machine and a lever one of the ends of which is in contact with said cam. The other end of said lever, the position of which is modified by the rotary movement of the cam, forms a stop of variable position adapted to coact with a pivoting toothed lever in mesh with the toothed sector that forms the rack. When the contact device comes into register with one of the perforations of the card (synchronously with the position of the type carrying wheel, the contact organ being in register with the line of the card that corresponds to letter A when the type marked A of the type carrying wheel is in a position such that it can be printed) the toothed sector acting as a rack is immediately caused, through the transmission existing between the contact device and the selecting device, to come into contact with one of the toothed wheels of the movable carriage. At the same time, the toothed lever in mesh with said sector is prevented from moving by the lever resting on the cam. Under these conditions, the toothed sector that acts as a cam is fixed on its axis and the carriage immediately brings the type carrying wheel into the printing position. If, on the contrary, the contact organ comes into register with a perforation of the first lines of the card (reserved lines), which perforation has only a meaning if combined with a second perforation of one of the following lines, the toothed sector is not immediately applied against one of the toothed wheels of the carriage, due to the action of a second cam which then locks the lever that carries this sector. The application of the toothed sector against one of the toothed wheels of the carriage takes place only when the contact organ meets another perforation, while the lever associated with the selecting cam is locked, by a device brought into action by the meeting of the first perforation with the contact organ, in such a position that it leaves to the toothed support in mesh with the sector a freedom of movement which varies according to the rank of the line in which was the first perforation. It follows that the toothed sector is not locked in a fixed position when it comes into contact with one of the toothed wheels of the carriage. It therefore rotates about its axis through a certain angle corresponding to the freedom of movement left by the selecting lever to the toothed support. When the toothed sector has moved through said angle, it is locked in its present position and the type carrying wheel is brought into its printing position. The distance between the type that is printed on the paper and the immediately preceding type of the

first series of characters (characters corresponding to a single perforation) corresponds to the freedom that has been left by the selecting lever to the toothed support in mesh with the sector that acts as a rack.

A preferred embodiment of my invention will be hereinafter described with reference to the accompanying drawings, given merely by way of example, and in which:

Figs. 1 to 4 inclusive each show a vertical diagrammatic sectional view of a printing device according to my invention, these respective views showing the apparatus in different positions of its operation;

Fig. 1 shows the apparatus in the position of rest;

Fig. 2 shows the apparatus in the position that corresponds to the printing of a character of the first series, corresponding to a single perforation of the card (in the specific example shown in Fig. 2, letter A);

Fig. 3 shows the apparatus in the position corresponding to the printing of a character or sign of the second series, corresponding to two perforations one of which is located in the first line of the card (in the drawing character K);

Fig. 4 is a similar view corresponding to the printing of a character or sign of the third series, corresponding to two perforations one of which is located on the second line of the card (in the example, character U);

Fig. 5 is a partial end view of the machine;

Fig. 6 is a plan view of a perforated card showing the arrangement utilized according to my invention.

35

The whole of the printing devices, one of which is shown on any of the views of Figs. 1 to 4 inclusive, is driven by a common shaft 1 which turns synchronously with the tabulating machine so that the type carrying wheels 7 of all the printing devices may turn one revolution for each perforated card passing through the contact device of the machine.

The tabulating machine may be either wholly mechanical or electrical. In the example that has just been described in the drawings, it is electrical, so that every perforation of a card admitted through the machine produces, at the time of its passing in front of the contact device, an electric current which is conveyed to the electro magnet that controls the printing device corresponding to said contact device and brings said device into action.

The columns of a statistical card generally comprise only twelve lines of perforations, as shown in Fig. 6. In order to represent, through said perforations, thirty characters or signs or even more, I utilize, according to my invention, a system of perforations, an example of which is shown in Fig. 6. The two lines of the perforated card that are first met by the contact device, that is to say lines 9 and 8 (the card being supposed to pass through the tabulating machine in the direction of arrow F) are reserved, and do not indicate by themselves any character or sign.

The thirty characters to be represented are divided into three series.

In the first series, which goes from A to J, each character is represented by a perforation in one of the lines following the third line inclusive (line 7) reckoning in the direction in which the contact device moves relatively to the card.

In the second series, the characters are repre-

sented by the combination of a perforation in line 9 and a perforation in one of the lines beginning at line 7.

In the third series, beginning at letter U, the 5 characters are represented by the combination of a perforation in line 8 and a perforation in one of the lines beginning at line 7.

Instead of 30 characters, I might as well represent more, by reserving for instance line 7 as 10 shown in the portion of Fig. 6 located on the right hand side of the dotted line.

The machine which will be described with reference to Figs. 1 to 4 corresponds to a card containing only 30 characters, that is to say, perforated according to the system shown in the left hand side of Fig. 6.

I will now describe with reference to the drawings, the structure of one printing device, it being well understood that that description applies to all the others.

Main shaft 1, which runs over the whole length of the machine, is provided with pinions 2 keyed thereon and meshing with a toothed wheel 3. Wheel 3 is rigidly fixed to toothed wheel 4 which 25 drives toothed wheel 6 through intermediate wheel 5. Wheel 6 is rigidly fixed to type-carrying wheel 7 over the circumference of which the types are distributed with a three-spacing arrangement as above explained, and as shown in Fig. 1.

Wheels 3, 4, 5, 6 and 7 revolve about their 30 spindles 30, 32 and 33, which are fixed on movable support or carrier 31. Shaft 1 is connected with the tabulating machine in such manner that wheel 3 and type-carrying wheel 7 turn synchronously with the tabulating machine. In other words, every time a perforated card passes through the tabulating machine, wheel 3 and type-carrying wheel 7 make a complete turn. Support 31 is provided with three projections or 35 arms 34, 35 and 36. On arm 34 there is fixed pin 37 about which is pivoted connecting rod 38. The other end of said connecting rod is pivoted at 39 to support 41 integral with the frame of the machine. Arm 35 is provided with a pin 42 40 carrying a roller 43 running along the guiding surface 55 of lever 44. The third arm, 36, has a surface 45 against which rests a roller 46 carried by a pin 47 fixed to a lever 48 pivoted about spindle 49. At the other end 50 of lever 48, there 45 is fixed a spiral spring 51 attached at 52 to support 53 rigidly fixed to the frame. Spring 51 tends to push lever 48 and roller 46 against the arm 36 of support 31, so that said support 31 and roller 43 carried by arm 35 are applied 50 against the guiding surface 55 of lever 44 which is provided with a small projection 423. Lever 44 is pivoted about spindle 54, and its end 59 is attached to a spiral spring 60 fixed to stationary support 61. Said spring 60 tends to apply lever 55 60 44 against the lower part 62 of support 61.

The type-carrying wheel 7, when in position of rest, bears against inking cylinder 63, so that when wheel 7 rotates, types 8 roll upon the inking cylinder 63. Paper cylinder 64, which carries 65 paper 65, guided by members 66, and which is adapted to revolve about its axis, is locked in a suitable manner during the printing operation.

A bar 67 carried at both ends by levers 69 pivoted about spindle 70 integral with the frame of 70 the machine, serves to bring movable support 31 from its upper position, or printing position, (Figs. 2 to 4) to its lower position or position of rest (Fig. 1) by bearing against a projection 68 of said support. Levers 69 are each provided 75 with a spindle 74 carrying a roller 75. Said roller

75 is applied against a cam 19 by spring 72 which is fixed to lever 69 at 71 and to the frame of the machine at 73. The rotation of cam 19, which takes place synchronously with that of shaft 1, and consequently with that of the tabulating 5 machine, as will be hereinafter described, therefore causes support 31 to be brought back into its position of rest through the action of bar 67 and projection 68.

Support 76, which is integral with the frame 10 of the machine, carries two spindles 77 and 78 about which lever 79 on the one hand, and levers 80 and 81 on the other hand, are respectively pivoted. The end 83 of lever 79 is maintained in the position shown in Fig. 1 by a projection 84 15 of lever 85. Lever 79 is provided at its upper part with two teeth 86 and 87 which may engage with a tooth 88 of lever 89. A spring 92 fixed at 91 to lever 79, and at 91^a to a support 93 integral with the frame of the machine tends to apply a 20 boss 90 of lever 79 against a cam 29.

Lever 80 carries at its upper part a set of teeth 94 and a second set of teeth consisting of three stop teeth 95, 96, 97. At its lower part said lever carries a spindle 101 on which is journalled a 25 roller 102. A spring 99 fixed to lever 80 at 98, the other end of which is fixed to a support 100, rigidly connected to support 76, serves to maintain said lever 80 in the position shown in Fig. 1 in which its lower part is applied against the 30 edge of said support 100.

Lever 81 carries at its left hand end, a spindle 108 about which a toothed section 109 meshing with the teeth 94 of lever 80, can pivot. The end 103 of lever 81 is maintained in the position 35 of Fig. 1 by the projection 84 of lever 85, which also locks the end 83 of lever 79 in position as above stated. In its middle part, lever 81 carries a spindle 106 provided with a roller 107 which spring 104, fixed to support 105 integral with the 40 frame, tends to apply against cam 22.

Lever 89 can pivot about spindle 110 fixed to support 111 integral with the frame. Said lever 89 is provided at its upper end with a spindle 112 carrying a roller 113 which a spring 114, fixed to 45 bar 105 integral with the frame, applies against cam 24. The left end of said lever 89 forms a stop 115 and is provided with a tooth 88.

Lever 85 pivots about spindle 116 fixed to support 117 integral with the frame of the machine. 50 It carries at its upper part projection 84 that serves to lock levers 79 and 81 in position, and at its lower end the spindle 118 about which is pivoted connecting rod 119 pivoted at the other end to lever 120. Said lever 120 is fixed to the 55 armature 121 of electro-magnet 122, which is electrically connected to the contact device that corresponds to the printing device that is considered. A spring 126 fixed to bar 129 integral with the frame, serves to bring lever 85 back into 60 the position of Fig. 1.

Toothed wheel 9, carried by main shaft 1, is in mesh with a toothed wheel 10 which is keyed on a shaft 11 carrying a cam 12 which runs over its whole length. Toothed wheel 9 is also in 65 mesh with a toothed wheel 13, which is keyed, same as toothed wheel 14, on shaft 15 journalled in the frame. Toothed wheel 14 meshes with wheel 16 which is connected through toothed wheel 20 with toothed wheels 23 and 57. 70

Wheel 16 is carried by shaft 17 which carries at one of its ends a cam 19 and over its whole length cam 18. Wheel 20 is keyed on shaft 21 carrying cam 22 which extends over its whole length. Wheel 23 is keyed on shaft 24 carrying 75

cam 25, and wheel 57 is keyed on shaft 28 carrying cam 29. The toothed wheels have diameters such that shafts 11, 17, 21, 24 and 28 turn synchronously with wheel 3 and type-carrying wheel 7, in such manner that when wheel 3 makes a turn, the other shafts also make a turn.

To each type-carrying wheel of a printing device, there corresponds a movable support 31, toothed wheels 3, 4, 5, 6 and 7, levers 79, 80, 81, 89, 44, 48 and 85, connecting rods 38 and 119 and electro-magnet 122.

On the contrary, the following organs are common to all the printing devices, therefore to all the type-carrying wheels, to wit, cam shafts 17, 21, 24, 28 and 57, spindles 39, 54, 77, 78, 110 and 116, supports 41, 53, 76, 111 and 117, paper cylinder 64, inking cylinder 63, and finally supports 52, 62, 93, 100 and 105. The organs for driving the camshafts are mounted outside of the frame (Fig. 4).

The camshafts are so adjusted that when the contact device is located above the first line of the perforated card (designated by reference number 9 in Fig. 6) roller 113 of lever 89 rests against portion 25 of cam 24, and roller 106 of lever 81 rests against a portion 22 of cam 21, said lever 81 being thus locked in position.

As the card further moves in the direction of arrow F (Fig. 6) the contact organ passes over line 8 and cam 24 has now turned through an angle such that roller 113 of lever 89 rests against portion 26 of said cam, portion 22 of cam 21 still blocking lever 81.

It will first be supposed that there was no perforation in lines 9 and 8 of the card, but only one perforation in line 7, which perforation corresponds to letter A, according to the arrangement illustrated in Fig. 6. During the forward movement of the card, which brings line 7 under the contact device, cam 24 further rotates so that roller 113 of lever 89 rests upon portion 27 of said cam, while the projecting portion 22 of cam 21 is no longer in contact with roller 106 of lever 81 (Fig. 2).

Due to the presence of a perforation in line 7, the contact device closes the circuit of electro-magnet 122, which draws armature 121 towards itself. Said armature rotates about its axis 123 and causes lever 85 to rotate in a likewise manner due to the presence of connecting rod 119. Levers 79 and 81 are released by hook 84, and rotate about their respective axes 78 and 77 in an anti-clockwise direction under the action of springs 92 and 104 respectively.

The fact that lever 79 is released has no effect whatever at the present time, because the projection 90 of said lever is now resting against cam 29. The movement of lever 81 causes toothed sector 109 to come into mesh with toothed wheel 3 and to turn through a small angle about its axis 108, due to its being in mesh with teeth 94 of lever 80. Teeth 94 are themselves stationary because lever 80 is blocked by the end 115 of lever 89 which rests upon projection 97 of lever 80. Wheel 3, which is constantly rotated by main shaft 1, is therefore instantly stopped at the point where it meshes with sector 109. It therefore rolls along the teeth of sector 109 so that its spindle and support 31 are given an upward translatory movement.

In the course of this movement, the velocity of the tooth of wheel 3 that is in contact with sector 109 is equal to zero, and it follows that the character A of the type-carrying wheel, which occupies on said wheel a place correspond-

ing to the above mentioned tooth of wheel 3 that is blocked, has also a vertical velocity which is equal to zero. This results from the synchronism of the rotary motions of wheels 3 and 7, and from the fact that the distance from the types to the centre of wheel 7 is equal to the pitch radius of toothed wheel 3.

In the course of the upward movement of support 31, roller 43 strikes projection 123 of surface 55, thus imparting to support 31 and to the type-carrying wheel, a sudden movement toward the paper. Type A of the type-carrying wheel, the vertical velocity of which at this time is equal to zero, is then struck against the paper and printed.

As projection 123 is very short in the vertical direction, roller 43 passes very quickly over said projection, and the type-carrying wheel together with support 31 oscillates towards the left hand side of the figure under the action of spring 51 transmitted through lever 48 and roller 46.

Lever 44 may be so adjusted that if roller 42 moves slowly past projection 123, the type-carrying wheel does not touch the paper, and that only when the machine is working at high speed does 25 the striking of roller 43 against projection 123 give the type-carrying wheel sufficient acceleration in order that it may reach the paper and strike a character against said paper substantially in the same manner that the types of an 30 ordinary typewriter are struck on the cylinder.

Support 31 subsequently reaches its upper position, in which it is locked by roller 46 which bears against the lower face of surface 45, until it is brought back into its initial position 35 by bar 67 as above explained.

While support 31 is moving down, cam 12, which bears against projection 56, causes lever 44 to turn in an anti-clockwise direction so that roller 43 does not come into contact with projection 123, and the type-carrying wheel remains applied against inking roller 63. During the same time, cam 25 lifts lever 89, while cams 29 and 22 bring levers 79 and 81 back into their initial position in which said levers are locked 45 by the hook 84 of lever 85. Cam 18 acts as a safety organ which imperatively brings lever 80 back into its initial position.

Every time a column is provided with a single perforation in line 7 of the card, the lower device corresponding to the contact organ of said column will print character A in the manner which has just been described.

If, in the column in question, the card is provided with a single perforation located in line 55 6 corresponding to letter B, the contact will be produced only when said perforation comes under the contact device, that is to say, when wheel 3 and the type-carrying wheel of the corresponding printing device have moved forward 60 through an angular displacement corresponding to three teeth with respect to the position that they occupy when the contact device was over line 7. While the electro-magnet is energized, sector 109 comes into mesh with a tooth of wheel 65 3 which is distant from the position above considered on wheel 3 by three teeth. Therefore, the type that comes into the printing position is also distant by three types from the position above considered on type-carrying wheel 7. Said type 70 therefore corresponds to letter B as shown in Fig. 1.

The perforation in line 5 of the card produces in the same manner the meshing of sector 109 with a tooth that is three more teeth distant 75

along wheel 3, that is to say, six teeth behind the tooth of wheel 3 that comes into contact with sector 109 when the perforation is made in line 1 of the card.

5 Letters A to G each represented by a single perforation as shown in Fig. 6 are distributed over the periphery of type-carrying wheel 7 with an interval of three teeth between two consecutive letters. The two intermediate types of each 10 interval correspond to a group of two perforations in each column of the card, and I will now explain how said types are printed.

As shown in Fig. 6, letters K to T are each represented by two perforations, one of which 15 is in line "9".

It will first be supposed that the card is perforated in the column in question at lines 9 and 7 (letter K).

When perforation 9 comes above the contact 20 device, roller 113 is applied against the portion 25 of cam 24, and projection 22 of cam 21 locks lever 81. When the electro-magnet is energized, lever 85 releases levers 79 and 81. Lever 79 rotates under the action of spring 92. Tooth 86 25 engages in tooth 88 and locks lever 89 in its position. Lever 81 cannot move since it is blocked by cam 22. When the card is moved forward, perforation 9 is no longer under the contact device, the electric circuit is cut off, the electro- 30 magnet is no longer energized and the hook 84 of lever 85 comes back above the end 103 of lever 81 which is thus locked.

As the card further moves, the passage of perforation 7 under the contact again causes the 35 electro-magnet 122 to be energized and lever 85 again releases lever 81. The projection 22 of cam 21 is no longer located opposite roller 107, and lever 81 can rotate about its axis 78 under the action of spring 104. Sector 109 comes into 40 mesh with wheel 3 as above explained, but as lever 89 is stopped by tooth 86 in the position shown in Fig. 3, lever 80 is maintained in its position merely by the weak spring 98 which applies it against bar 100.

45 When sector 109 comes into mesh with wheel 3, the latter, rotating with a certain speed of revolution in the direction of the arrow, drives sector 109 in an anti-clockwise direction. Sector 108, by rotating about its spindle 109 transmits 50 the movement of wheel 3 to toothed part 94, and lever 80 is swung until tooth 95 strikes the end 115 of lever 89. Lever 80 stops in that position in which it is blocked by lever 89 (Fig. 3). As toothed part 94 is now stationary, sector 109 55 is in turn blocked and acts as a rack for wheel 103 which is compelled to move upwardly by rolling thereon. The swinging movement of lever 80 corresponds to a rotation of two teeth of wheel 3, which means that the tooth of wheel 3 that is stopped by sector 109 and the velocity of which is equal to zero, is distant from the tooth that was stopped for the printing of character "A" by an interval corresponding to two teeth of wheel 3. Consequently, the type of the type-carrying wheel which is now in printing position is distant from the type corresponding to character "A" by an interval corresponding to two successive teeth of said type-carrying wheel 7.

60 It will now be assumed that the card is perforated in the column in question in lines 8 and 7 (character "U"). When perforation 8 passes under the contact device, roller 113 rests upon portion 26 of cam 24, the electro-magnet is energized and lever 79 is released by hook 84 and 65 locks lever 89 by tooth 87 in the position shown

in Fig. 3. Once the circuit is cut off, lever 85 again blocks lever 81 which up to now was blocked by projection 22 of cam 21. When perforation 7 passes under the contact device, the electro-magnet is again energized. Lever 81 is released 5 by hook 84 and toothed sector 109 comes into mesh with exactly the same tooth of wheel 3 as when characters "A" or "K" were to be typed. Due to this meshing, sector 109 turns about its axis 108, and lever 80 swings until tooth 96 strikes 10 stop 115 of lever 89 (Fig. 4). Wheel 3 then moves upwardly by rolling on sector 109 which is stationary. The type that is printed is therefore distant from character "A" by an interval corresponding to one type of the circumference of 15 type-carrying wheel 7.

It will now be understood how the perforations of lines 8 and 9 of the card produces the backward movement of lever 80. The meshing of sector 109 with wheel 3 is controlled by the ordinary perforations indicated on the card by a number equal to or smaller than 7, and the meshing is exactly the same whether or not there is in the column a supplementary perforation in 25 line 8 or 9.

Once this meshing has taken place, wheel 3 moves upwardly with a rolling movement in three different ways accordingly as there are supplementary perforations or not, by printing one of the three different consecutive characters of the 30 type-carrying wheel. In the case in question, the arrangement comprises ten ordinary perforations and two supplementary perforations which permits to represent 30 different characters as shown in the first thirty columns of the card 35 shown in Fig. 6. But the system above described can also be utilized for printing more than thirty characters, for instance by utilizing perforations in lines 9, 8 and 7 as supplementary perforations, and the perforations in lines of lower number than 7, as ordinary perforations. This arrangement is shown in the last column 9 of the card shown in Fig. 6. In this case, lever 80 would be provided with a fourth tooth (besides teeth 95, 96, 97), cam 24 would be provided with 40 a fourth stop (besides stops 25, 26, 27) lever 79 would be provided with a third tooth (besides tooth 86, 87) and projection 22 of cam 21 would be lengthened so as to still block lever 81 when 45 perforation 7 arrives under the contact organ. 50

The type-carrying wheel would be of greater dimensions, and would comprise 39 types and wheel 3 would be provided with 15 supplementary teeth.

It would be still easier to utilize merely one 55 perforation for the figures and a combination of two perforations for the letters. The movement would take place as above described, and it is not necessary to explain how this system would 60 then work.

While I have described what I deem to be practical and efficient embodiments of my invention, it should be well understood that I do not wish to be limited thereto, as there might be changes 65 made in the arrangement, disposition and form of the parts without departing from the principle of my invention as comprehended within the scope of the appended claims.

What I claim is:

70 1. A printing machine especially adapted to be used in connection with tabulating or similar machines for perforated cards, which comprises in combination, a stationary frame, a paper cylinder journaled in said frame, a support 75

adapted to move with a translatory motion with respect to said frame in a direction substantially at right angles to the axis of said cylinder, a type-carrying wheel journalled on said support, a plurality of types along the periphery of said wheel, a toothed wheel rigidly fixed to said type-carrying wheel in coaxial relation therewith, another toothed wheel parallel to the first mentioned one and of equal diameter journalled on said support and adapted to rotate synchronously with the first mentioned wheel, means for driving the last mentioned toothed wheel, means for stopping one point of the periphery of the last mentioned toothed wheel so that said wheel is compelled to roll about said stopping means, and means for imparting to said support a movement at right angles to its translatory motion during said rolling movement of the last mentioned wheel.

20. 2. A printing machine especially adapted to be used in connection with tabulating or similar machines for perforated cards, which comprises in combination, a stationary frame, a paper cylinder journalled in said frame, a movable support of elongated shape extending in a direction substantially at right angles to the axis of said cylinder, a member carried by said frame and having a guiding surface substantially parallel to the general direction of said support, an arm rigidly fixed to said support, a roller carried by said arm adapted to cooperate with said guiding surface, a projection at a point of said guiding surface, a connecting rod pivoted at one end to said frame and at the other end to said support, a type-carrying wheel journalled on said support about an axis parallel to said cylinder, a plurality of types along the periphery of said wheel, a toothed wheel rigidly fixed to said type carrying wheel in coaxial relation therewith, another toothed wheel parallel to the first mentioned one, and of equal diameter, journalled on said support, positive means for angularly connecting said toothed wheels together so that they rotate synchronously, means for driving the last mentioned toothed wheel, and means for stopping one point of the periphery of the last mentioned toothed wheel so that it is compelled to roll along said stopping means.

30. 3. A printing device according to claim 2 in which the member having a guiding surface consists of a lever pivoted to said frame, said device further comprising means, including an elastic organ, for keeping said lever in cooperating relation with said roller for one direction of displacement of said roller with respect to said guiding surface, means for bringing back said support to its initial position after its movement in said direction, and means for moving said lever during the movement of the support in the opposite direction, against the action of said elastic organ, so that said roller no longer runs along said guiding surface.

40. 4. A printing machine especially adapted to be used in connection with tabulating or similar machines for perforated cards, which comprises in combination, a stationary frame, a paper cylinder journalled in said frame, a type-carrying wheel, a plurality of types along the periphery of said wheel, a support for said type-carrying wheel adapted to move with a translatory motion with respect to said frame, a toothed wheel carried by said support and adapted to rotate synchronously with said type-carrying wheel, means for driving said toothed wheel, means for stopping one point

of the periphery of the toothed wheel so that said toothed wheel is compelled to roll along said stopping means, means for bringing said stopping means into contact with said toothed wheel, and means for allowing said stopping means to move together with the last mentioned wheel to a determined limited extent. 5

5. A printing machine especially adapted to be used in connection with tabulating or similar machines for perforated cards, which comprises in combination, a stationary frame, a paper cylinder journaled in said frame, a support adapted to move with a translatory motion with respect to said frame, a type-carrying wheel journaled on said support, a plurality of types along the periphery of said wheel, a toothed wheel rigidly fixed to said type-carrying wheel in coaxial relation therewith, another toothed wheel of equal diameter journaled on said support, a pinion journaled on said support and meshing with the above mentioned toothed wheels so that they rotate at the same speed of revolution and in the same direction, a main driving shaft for the machine, a toothed wheel on said shaft imperatively connected with the last mentioned toothed wheel, a lever pivoted to said frame, a toothed sector journaled on said lever and adapted to mesh with the second mentioned toothed wheel, means for rotating the last mentioned lever so as to bring said sector into mesh with the second mentioned toothed wheel, another lever journaled on said frame about the same axis as the last mentioned lever, a toothed sector formed in the last mentioned lever constantly in mesh with the first mentioned toothed sector, and means for stopping the last mentioned lever in a given angular position.

6. A printing machine especially adapted to be used in connection with tabulating or similar machines for perforated cards, which comprises in combination, a stationary frame, a paper cylinder journaled in said frame, a support adapted to move with a translatory motion with respect to said frame, a type-carrying wheel journaled on said support, a plurality of wheels along the periphery of said wheel, a toothed wheel rigidly fixed to said type-carrying wheel in coaxial relation therewith, another toothed wheel of equal diameter journaled on said support, a pinion journaled on said support and meshing with the above mentioned toothed wheels so that they rotate at the same speed of revolution and in the same direction, a main driving shaft for the machine, a toothed wheel on said shaft operatively connected with the last mentioned toothed wheel, a lever pivoted to said frame, a toothed sector journaled on said lever and adapted to mesh with the second mentioned wheel, another lever journaled in said frame about the same axis as the last mentioned lever, a third lever journaled in said frame, a roller carried by said third lever, a cam rotating synchronously with said main shaft adapted to cooperate with the last mentioned roller, a fourth lever journaled in said frame, elastic means for rotating the last mentioned lever, locking means for normally preventing the last mentioned lever to rotate under the action of said elastic means, means carried by said fourth lever for blocking the third lever in the position which it occupies when said fourth lever is released by the last mentioned locking means, a plurality of stops carried by the second lever adapted to cooperate with the corresponding portion of the third lever so that said second lever is stopped by said third lever in a certain position

depending on the position of said third lever, a plurality of teeth carried by said second lever and constantly in mesh with said toothed sector, elastic means for rotating said first lever into mesh with said second mentioned toothed wheel, locking means for preventing the action of the last mentioned elastic means, and a cam rotating synchronously with said main shaft for keeping the fourth lever in its position of rest against the action of the elastic means that cooperate therewith, during a certain period of the rotation of said last mentioned cam.

7. A printing machine especially adapted to be used in connection with tabulating or similar machines for perforated cards, which comprises in combination, a stationary frame, a paper cylinder journalled in said frame, a movable support of elongated shape extending in a direction substantially at right angles to the axis of said cylinder, a member pivoted to said frame and having a guiding surface substantially parallel to the general direction of said support, an arm rigidly fixed to said support, a roller carried by said arm adapted to cooperate with said guiding surface, elastic means for applying said roller against said guiding surface, a projection at a point of said guiding surface means for moving said member out of cooperating engagement with said roller for one direction of displacement of said support, a connecting rod pivoted at one end to said frame and at the other end to said support, a type-carrying wheel journalled on said support, a plurality of types along the periphery of said wheel, a toothed wheel rigidly fixed to said type-carrying wheel in coaxial relation therewith, another toothed wheel of equal diameter journalled on said support, a pinion journalled on said support and meshing with both of the above mentioned toothed wheels so that they rotate at the same speed of revolution and in the same direction, a main driving shaft for the machine, a pinion on said shaft operatively connected with the last mentioned toothed wheel, a lever pivoted to said frame, a toothed sector journalled on said lever and adapted to mesh with the second mentioned wheel, another lever journalled in said frame about the same axis as the last mentioned lever, a third lever journalled in said frame, a roller carried by said third lever, a cam rotating synchronously with said main shaft adapted to cooperate with the last mentioned roller, a fourth lever journalled in said frame, elastic means for rotating the last mentioned lever, locking means for normally preventing the last mentioned lever to rotate under the action of said elastic means, means carried by said fourth lever for blocking the third lever in the position which it occupies when said fourth lever is released by the last mentioned locking means, a plurality of stops carried by the second lever adapted to cooperate with the corresponding portion of the third lever so that said second lever is stopped by said third lever in a certain position depending on the position of said third lever, a plurality of teeth carried by said second lever and constantly in mesh with said toothed sector, elastic means for rotating said first lever into mesh with said second mentioned toothed wheel, locking means for preventing the action of the last mentioned elastic means, and a cam rotating synchronously with said main shaft for keeping the fourth lever in its position of rest against the action of the elastic means that cooperate therewith, during a certain period of the rotation of said last mentioned cam.

9. In combination with a tabulating or similar machine utilizing perforated cards, a printing machine comprising a stationary frame, a paper supporting platen, a support adapted to move with a translatory motion with respect to said frame in a direction substantially at right angles to the axis of said platen, a typewheel having a plurality of type elements on the periphery thereof, means for imparting both translational and rotational motion to the typewheel so that said type wheel performs a rolling motion in respect to the paper on the platen, and means for imparting to said support a movement at right angles to its translatory motion during said rolling motion of the typewheel.

10. In combination with a tabulating or similar machine utilizing perforated cards, a printing machine comprising a stationary frame, a paper supporting platen, a support adapted to move with a translatory motion with respect to said frame in a direction substantially at right angles to the axis of said platen, a typewheel having a plurality of type elements on the periphery thereof, means to rotate said wheel, blocking means adapted to cooperate with said rotating typewheel for changing said rotation to both translational and rotational motion of the typewheel so that the typewheel performs a rolling motion with respect to the paper on the platen, said blocking means being so arranged as to be able to move after its initial engagement with the typewheel, so that the typewheel is allowed to

8. A printing machine especially adapted to be used in connection with tabulating or similar machines for perforated cards, which comprises in combination, a stationary frame, a paper cylinder journalled in said frame, a movable support of elongated shape extending in a direction substantially at right angles to the axis of said cylinder, a member pivoted to said frame and having a guiding surface substantially parallel to the general direction of said support, an arm rigidly fixed to said support, a roller carried by said arm adapted to cooperate with said guiding surface, elastic means for applying said roller against said guiding surface, a projection at a point of said guiding surface means for moving said member out of cooperating engagement with said roller for one direction of displacement of said support, a connecting rod pivoted at one end to said frame and at the other end to said support, a type-carrying wheel journalled on said

turn through a certain angle dependent on the above mentioned movement of the blocking means, and means for stopping said movement of the blocking means in different positions thereof whereby different groups of characters may be printed.

11. A printing machine especially adapted to be used in connection with a tabulating machine for perforated cards and the like, comprising a stationary frame, a platen, a typewheel support, a typewheel rotatably mounted on said support adjacent said platen, said typewheel having a plurality of type elements on the periphery thereof, means for imparting to the typewheel support a translatory movement with respect to the platen, in a plane substantially at right angles to said platen, means for imparting to the typewheel rotary movement in addition to the translatory movement derived from its support, such that it performs a rolling movement in relation to the platen in a plane substantially at right angles to the said platen, and means for giving the typewheel during said rolling movement, an additional movement directed against the platen, whereby the typewheel strikes the platen.

12. A printing machine especially adapted to be used in connection with a tabulating machine for perforated cards and the like, comprising a stationary frame, a platen, a typewheel support, a typewheel rotatably mounted on said support adjacent said platen, said typewheel having a plurality of type elements on the periphery thereof, means for imparting to the typewheel support a translatory movement with respect to the platen, in a plane substantially at right angles to said platen, means for imparting to the typewheel rotary movement in addition to the translatory movement derived from its support, such that it performs a rolling movement in relation to the platen in a plane substantially at right angles to the said platen, means for giving the typewheel during said rolling movement, an additional movement directed against the platen, whereby the typewheel strikes the platen, and means permitting the typewheel to spring back in the very moment it hits the platen.

13. A printing machine especially adapted to be used in connection with a tabulating machine for perforated cards and the like, comprising a stationary frame, a platen, a typewheel support, a typewheel rotatably mounted on said support adjacent said platen, means for rotating said typewheel, means for imparting to the typewheel support a translatory movement with respect to the platen in a plane substantially at right angles to the platen, blocking means adapted to cooperate with a toothed wheel having driving engagement with the typewheel, means for engaging the blocking means with the said toothed wheel, means for moving the blocking means after it has been engaged with the typewheel, allowing the typewheel to continue its rotation, means for immobilizing the blocking means in different positions after it has been engaged with the typewheel, means whereby when the blocking means has been immobilized, there is imparted to the typewheel a rolling movement with respect to the platen as a result of the movement of said support, in a plane substantially at right angles to said platen, means for printing a selected one of the types on the typewheel during said rolling

movement, and means whereby a different group of types may be printed for each determined position in which the blocking means has been immobilized.

14. A printing machine especially adapted to be used in connection with a tabulating machine for perforated cards and the like, comprising a platen, a typewheel support, a typewheel rotatably mounted on said support adjacent said platen, said typewheel having a plurality of fixed type elements spaced along the periphery thereof of which type elements belong to different groups of types, means for rotating the typewheel, means for selecting, without stopping or modifying the rotation of the typewheel, the group to which the type to be printed belongs, means for selecting within each group the type to be printed, means whereby in order to print one single determined type, both the group selection and the type selection may be initiated and completely executed and the type printed during one single revolution of the typewheel, and means whereby the typewheel may be ready to print another type without changing its direction of rotation.

15. A printing machine especially adapted to be used in connection with a tabulating machine for perforated cards and the like, comprising a platen, a typewheel support, a typewheel rotatably mounted on said support adjacent said platen, said typewheel having a plurality of type elements on the periphery thereof, which type elements belong to different groups of types, means for rotating the typewheel, means for selecting without stopping or modifying the rotation of the typewheel, the group to which the type to be printed belongs, means for selecting within each selected group the type to be printed, said means for group selecting and type selecting comprising one single magnet for each typewheel, an armature for said magnet controlling both said selecting means and a separate control for said second selecting means adapted to maintain it inactive on the first energization of said magnet, whereby the group is selected when said magnet is energized the first time during a cycle of the machine, and the type to be printed within the selected group is selected when said magnet is energized the second time during said cycle.

16. A printing machine especially adapted to be used in connection with a tabulating machine for perforated cards and the like, comprising a platen, a typewheel support, a typewheel rotatably mounted on said support adjacent said platen, said typewheel having a plurality of type elements fixed on the periphery thereof, which type elements belong to different groups of types, means for rotating the typewheel, means for selecting during the rotation of the typewheel the group to which the type to be printed belongs, means for selecting within each selected group the type to be printed, means for initiating and completing both of the said selecting operations during one single revolution of the typewheel, said selecting means being adapted to cooperate with a record card, whereby the lower indications on the card cooperate with the group selecting means and the higher indications on the card cooperate with the type selecting means.
